RIVET SETTING TOOL OR SIMILAR ARTICLE

Anthony E. Di Maio, Georgetown, Mass., assignor to
Marson Corporation, Chelsea, Mass.

Filed Apr. 19, 1971, Ser. No. 135,296

Term of patent 14 years

Int. Cl. D8—05

U.S. Cl. D8—51

FIG. 1 is a top plan view of a rivet setting tool or similar article showing my new design.

FIG. 2 is a side elevational view thereof.

FIG. 3 is a front elevational view thereof.

FIG. 4 is a side elevational view showing the side opposite to that shown in FIG. 2.

FIG. 5 is a bottom plan view thereof.

I claim:

An ornamental design for a rivet setting tool or similar article, as shown.
